UNITED STATES PATENT OFFICE.

ROBERT CRAWFORD JOHNSON, OF ROXTON, LEICESTER, ENGLAND.

BUTTON OR DISTANCE PIECE FOR SUPPORTING THE RUNNER RAILS OF CURTAINS.

Application filed February 26, 1926, Serial No. 90,905, and in Great Britain March 12, 1925.

This invention relates to buttons, distance-pieces or support brackets for the rails carrying the runners for curtains, of the kind in which a recess or housing is formed in each 5 button for the reception of the reeving cords such, for example, as is shown in my former Letters Patent of the United States, No. 1,628,984, dated May 17, 1927.

With this construction of button or distance-piece it is found that with the arrangement of the control and return cords in the single recess therein, the said cords tend to foul one another and the object of my invention is to obviate this disadvantage.

According to the invention I form each of the buttons or distance-pieces with two recesses or housings, one for the control cord and the other for the return cord.

In a suitable arrangement for carrying out 20 the invention both recesses are arranged side by side and open to the upper surface of each button or distance-piece, the recesses may be contracted or narrowed at the entrances thereto to about the width of the cords sufficient to allow of the insertion of the latter into the said recesses under easy pressure.

Alternatively, the buttons or distance-pieces may be arranged with the recesses one above the other and open to the inside surface of each button.

In either case, the recess for the return cord may be closed instead of open.

The face of the button which abuts against the surface to which it is to be secured is 35 advantageously formed with a projection or tooth which is pressed into the said surface and prevents the movement of the button when screwed in position.

To enable the invention to be fully understood I will describe it by reference to the accompanying drawing, in which:—

Figure 1 is a perspective view of a button or distance piece for supporting the runner rails of curtains, constructed in accordance 45 with the invention and

Figures 2, 3 and 4 are, respectively, a side view, an end view and a plan view thereof, Fig. 2, showing in dotted lines the supporting rod and one of the curtain runners with 50 which my improved distance piece is intended to be used.

Figure 5 is a side view illustrating a modification.

55 *a* is the button or distance-piece and *b*, *c* are the two recesses or housings therein for

the control cord and return cord, respectively, indicated in dotted lines at *i*, *j*, respectively. In Figures 1 and 2, these recesses *b*, *c* are arranged side by side and open to the upper surface of the button or distance-piece, as indicated at *d*, *e* respectively, each of the said recesses being shown contracted or narrowed at the entrance thereto to about the width of the cord designed to engage therewith so as to allow of the insertion of the cord into 65 the recess under easy pressure. This contraction or narrowing however, is not essential.

f is the projection or tooth formed on the face *g* of the button which abuts against the surface to which the latter is secured and designed to be pressed into the said surface to prevent movement of the button when secured in position by a screw or the like passed through the hole *h*.

Figure 5 shows a form of the improved button or distance-piece in which the recesses for the cords are one above the other and opening to the inside surface of the button.

In either of the described arrangements, the recess for the return cord may be closed instead of open for the insertion of the cord, the latter being threaded through the said recess.

Having now particularly described and ascertained the nature of my said invention and in what manner the same is to be performed I declare that what I claim is:—

1. A support bracket or distance piece for supporting the runner rail of curtains, provided with a vertical face to engage the surface to which the bracket is to be secured, and means for securing the bracket thereto, said bracket having a face provided with two transversely disposed parallel recesses extending entirely through the bracket, at least one of said recesses being open at its outer edge to receive the curtain control cord, the other of said recesses being constructed to receive the return cord and hold it separate from the control cord to prevent said cords from fouling.

2. A support bracket or distance piece for supporting the runner rail of curtains, provided with a vertical face to engage the surface to which the bracket is to be secured, said bracket having a face provided with two transversely disposed parallel recesses extending entirely through the bracket, at least one of said recesses being open at its

outer edge to receive the curtain control cord, the other of said recesses being constructed to receive the return cord and hold it separate from the control cord to prevent said cords from fouling, said bracket being provided with a hole longitudinally thereof for the passage of a supporting and securing

screw, and having its said abutting face provided with a projection located at a distance from said hole adapted to be pressed into the surface to which the bracket is secured to prevent movement of the bracket when secured in position by the screw. 10

ROBERT CRAWFORD JOHNSON.
